UNITED STATES PATENT OFFICE.

FREDERICK F. CHASE, OF PLAINFIELD, NEW JERSEY.

TICKET-HOLDER.

SPECIFICATION forming part of Letters Patent No. 424,642, dated April 1, 1890.

Application filed November 9, 1889. Serial No. 329,718. (No model.)

To all whom it may concern:

Be it known that I, FREDERICK F. CHASE, a citizen of the United States, residing in Plainfield, in the county of Union and State 5 of New Jersey, have invented an Improvement in Ticket-Holders, of which the following is a specification.

In railway traveling much inconvenience is experienced both to passengers and conductors from the frequent production of tickets, and holders have been attached to the backs of seats and in other convenient places into which the traveler's ticket can be inserted; but these holders have either been objectionable in appearance or liable to catch and injure the clothing when passing into or out of the seats.

The object of this invention is to furnish a reliable and inexpensive ticket-holder that 20 can be easily attached to a seat-back or in any other convenient place, and which will not have any angles or projections to catch or injure clothing, and into which the ticket can be freely inserted and securely held by moving it along in the slot provided for it.

In the drawings, Figure 1 is a plan view of the ticket-holder. Fig. 2 is an elevation of the same, and Fig. 3 is a cross-section in enlarged size.

30 This ticket-holder is made of india-rubber, there being an opening between the two parts of the rubber for the reception of the ticket.

The rubber may be in one piece with a central slit cut in it and parallel with the face; but I prefer to make use of two strips *ab* of rubber, that are similar and have holes near the ends for the passage of the attaching-screws *c*, and the adjacent faces of the rubber should be rounding to form a mouth or slit for the easy reception of the ticket, and such ticket 40 will be firmly held by moving it edgewise toward either screw *c*, the ticket passing to where the rubber presses it firmly on each surface.

The screws made use of should have smooth 45 and slightly-rounding heads, and a plate or strip of metal *d*, perforated near each end, may extend from one attaching-screw to the other and by its elasticity aid in holding the ticket.

50 I claim as my invention—

The ticket-holder formed of the two strips of elastic material *ab*, with a longitudinal tapering slit between them in their middle portions, the metal strip *d*, and the attaching- 55 screws passing through the metallic and elastic strips at the end portions, substantially as set forth.

Signed by me this 1st day of November, 1889.

FREDERICK F. CHASE.
